UNITED STATES PATENT OFFICE.

JAMES A. SCOTT, OF SOMERVILLE, MASSACHUSETTS, ASSIGNOR OF ONE HALF TO CHARLES E. FULLER, OF SOMERVILLE, MASSACHUSETTS.

PAPER BOX.

SPECIFICATION forming part of Letters Patent No. 738,633, dated September 8, 1903.

Application filed October 17, 1902. Serial No. 127,710. (No model.)

To all whom it may concern:

Be it known that I, JAMES A. SCOTT, of Somerville, in the county of Middlesex and State of Massachusetts, have invented certain new and useful Improvements in Paper Boxes, of which the following is a specification.

This invention relates to paper boxes, and particularly to that type of such box which is known as "neck-box."

10 The object of the invention is to provide a simple box of this type in which the top and bottom sections will be similar to or duplicates of each other.

15 A further object of the invention is to provide such a box which is collapsible or may be folded for transportation, thus making what is commonly termed a "knockdown" box.

20 To these ends the invention consists in the construction of the box, substantially as hereinafter described and claimed.

25 Of the accompanying drawings, Figure 1 is a perspective view of the main or bottom section of the box and the next section assembled. Fig. 2 represents a perspective view of the main or bottom section detached from the neck-section and with the closing-flaps partially opened. Fig. 3 represents a longitudinal section of the box embodying my present invention, the three sections of the box being 30 separate from each other. Fig. 4 represents a longitudinal section of a complete box embodying my present invention.

35 In the drawings the main or bottom section *a* is shown as provided with opposite flaps *a'* *a''* and with a bottom flap *a³* and a locking-flap *a⁴*, as clearly shown in Fig. 2, the said section being rectangular in form, scored in the ordinary manner to enable it to be collapsed into the flat condition when the flaps are unfolded.

40 The neck-section *b* comprises a simple rectangular open-ended section adapted to fit snugly within the section *a*. Said neck-section may be beveled at one end, as shown, or its two ends may be alike.

45 The cover-section *c* is practically identical in all respects with the main or bottom section *a*. As shown in Figs. 3 and 4, said cover-section *c* has opposite flaps *c'* *c''*, a top flap *c³*, and a locking-flap *c⁴*. This construction is obvious upon comparing Figs. 3 and 4, which

are sections at a right angle to each other through the parts of the box.

It will readily be understood that the three sections of the box may be easily assembled 55 and that owing to the fact that the bottom and cover sections are identical with each other it will make no difference which section is first applied to the neck-section *b*. When the flaps of the main and cover sections are opened, the entire box in assembled condition may be collapsed to a practically flat condition, either for transportation or for printing. The fact that the neck-box has similar or duplicate cover and bottom sections facilitates the assembling of the parts, 60 for the reason that it is not necessary that the person assembling the parts shall first note a difference, so as to determine which section is to be connected with the bottom of 65 the neck-section. Moreover, such construction reduces the number of changes which have to be made in the machine for cutting and scoring the blanks, for the reason that although three sections are employed in the 70 box there are but two kinds of sections.

75 It will be observed that the neck-section is shorter than the combined length of the cover and bottom sections, so that the inner ends of the last-mentioned sections meet when the 80 cover-section is in place upon the box and so that the locking-flap *c⁴* never engages the end of the neck-section, and consequently the repeated removal and replacing of the cover does not cause the bending of the said 85 flap *c⁴*. The locking-flap *a⁴*, on the contrary, is inserted between the adjacent walls of the neck and bottom sections after the bottom-flap *a³* has been folded interiorly of the opposite flaps *a'* *a''*, whereby it serves as a 90 wedge to frictionally hold the neck-section relatively against dislocation and also to prevent the dislocation of said bottom-flap.

I claim—

1. A shoulder or neck box comprising an 95 open-ended four-sided neck-section, and four-sided cover and bottom sections slidably and telescopically connected with said neck-section, said cover and bottom sections each having an end-closing flap with a locking-flap on 100 the extremity thereof, detachably inserted into the section to lie against the interior

surface of one of the sides thereof, said neck-section being shorter than the combined length of said cover and bottom sections, whereby the infolded locking-flap of the 5 cover-section escapes engagement with the upper end of the neck-section substantially as described.

2. A shoulder or neck box comprising a four-sided neck-section, and a four-sided 10 outer or bottom section telescopically connected therewith, said bottom section having

two oppositely-overlapping side flaps and a long flap folded exteriorly over said side flaps with its end inserted between the adjacent side walls of said neck-section and said outer 15 section.

In testimony whereof I have affixed my signature in presence of two witnesses.

JAMES A. SCOTT.
